UNITED STATES PATENT OFFICE.

WOLCOTT A. HULL, OF NEW YORK, N. Y.

DESIGN FOR A LAMP.

SPECIFICATION forming part of Design No. 17,848, dated November 1, 1887.

Application filed March 21, 1887. Serial No. 231,765. Term of patent 7 years.

To all whom it may concern:

Be it known that I, WOLCOTT A. HULL, of New York, in the county and State of New York, have originated and produced a new 5 Design for Lamps, of which the following is a specification.

My design will be best understood by reference to the accompanying drawing illustrating it. I will therefore describe the design in 10 conjunction with said drawing.

The drawing is a side elevation of a lamp embodying the design.

The foot-piece of the lamp may be of any desirable configuration, as it forms no part of 15 my design. The design consists of a reservoir having a convex upwardly-flaring lower portion, *a*, a band-like portion, *b*, at about the middle, a bead, *c*, at about the center of the band-like portion, a surmounting convex upwardly-contracted portion, *d*, a bead, *e*, at the 20 upper extremity of the portion *d*, and a conical portion, *f*, above the bead *e*. Above the conical portion *f* is a fillet or narrow cylindric portion, *g*, which is surmounted by a concave 25 molding, *h*.

The design also consists in the following features in the burner of the lamp, namely: a cylindric portion, *i*, a surmounting bead, *j*, a

perforated circular portion, *k*, flaring upwardly with an ogee curve, and a surmounting bead, *l*. 30

What I claim as my design, and desire to protect by Letters Patent, is—

1. The design for a lamp comprising a reservoir and a burner, consisting of a lower convex upwardly-flaring portion, *a*, a surmounting band-like portion, *b*, a bead, *c*, surrounding the band-like portion, a convex upwardly-contracted portion, *d*, surmounting the band-like portion, a bead, *e*, above the portion *d*, an upwardly-tapering or conical portion, *f*, above 35 the bead *e*, a cylindrical portion, *g*, a surmounting bead, *j*, a perforated circular portion, *k*, extending with an ogee curve upwardly from the bead *j*, and a surmounting bead, *l*, substantially as described and shown. 40

2. In a design for a lamp, the burner consisting of a cylindric lower portion, *i*, a surmounting bead, *j*, a perforated circular portion, *k*, extending with an ogee curve upwardly from the bead *j*, and a surmounting bead, *l*, substantially as shown and described. 45
